Patented Feb. 27, 1968

210,286

PRINTED CIRCUIT BOARD MODULE

William Venema, North Haledon, N.J., assignor to
Vemaline Products Company, Inc., Franklin Lakes,
N.J., a corporation of New Jersey

Filed May 15, 1967, Ser. No. 7,122

Term of patent 14 years

(Cl. D26—5)

FIG. 1

FIG. 2

FIG. 3

FIGURE 1 is a perspective view of the printed circuit board module of the present invention;

FIGURE 2 is a front plan view of the printed circuit board module of FIGURE 1;

FIGURE 3 is a right side view of the printed circuit board module of FIGURE 1.

A back plan view of the printed circuit board module of FIGURE 1 would be exactly like the front plan view of FIGURE 2.

The bottom of the printed circuit board module of FIGURE 1 is exactly like the top thereof as shown in FIGURE 1.

I claim:

The ornamental design for a printed circuit board module, substantially as shown and described.
